(57) **CLAIM**

The ornamental design for a collection container, as shown and described.

DESCRIPTION

FIG. 1 is a right side elevational view of a collection container showing our new design;

FIG. 2 is an enlarged front, top perspective view of the collection container design of FIG. 1;

FIG. 3 is a left side elevational view thereof;

FIG. 4 is a right side elevational view thereof;

FIG. 5 is a top plan view thereof;

FIG. 6 is a front view thereof;

FIG. 7 is a rear view thereof; and,

FIG. 8 is a bottom view thereof.

The broken lines immediately adjacent the shaded surfaces represents the bounds of the claim and all other broken lines are for illustrative purposes only. None of the broken lines form a part of the claimed design.
